(57) **CLAIM**

We claim the ornamental design for a decorative topper sign,
as shown and described herein.

DESCRIPTION

FIG. 1 is a perspective view of the decorative topper sign;

FIG. 2 is an enlarged front view of the device;

FIG. 3 is a left side view of the device;

FIG. 4 is a further enlarged right side view of the device;

FIG. 5 is a top side view of the device;

FIG. 6 is a bottom view of the device; and,

FIG. 7 is a back view of the device.

The broken lines shown in the figures are for illustrative
purposes only and form no part of the claimed design.
